R. C. DANLY

SNARE DRUM

Original Filed July 8, 1921

FIG. 1.

FIG. 2.

FIG. 5.

FIG. 4.

INVENTOR:

ROBERT C. DANLY,

BY

Robert C. Danly

ATTORNEY.

UNITED STATES PATENT OFFICE.

ROBERT C. DANLY, OF CHICAGO, ILLINOIS, ASSIGNOR TO LUDWIG & LUDWIG, INC., OF CHICAGO, ILLINOIS, A CORPORATION OF ILLINOIS.

SNARE DRUM.

Application filed July 8, 1921, Serial No. 483,154. Renewed June 25, 1923.

To all whom it may concern:

Be it known that I, ROBERT C. DANLY, a citizen of the United States of America, and a resident of Chicago, in the county of 5 Cook, State of Illinois, have invented certain new and useful Improvements in Snare Drums, of which the following is a specification.

This invention relates to means for moving the snares of snare drums into and out of their active position, and has for its 10 object:

To provide a structural formation and association of parts and mechanisms whereby the adjustable carriers of the snares are interconnected so as to move in unison to attain an even and uniform movement of the whole lengths of the snares towards and away from the surface of the drum head or 15 skin, and with which a predetermined tensioning of the snares is maintained without change during said movements, all as will hereinafter more fully appear.

In the accompanying drawing:—

25 Fig. 1, is detail central longitudinal sectional elevation of an end of a drum, with the preferred form of this invention applied thereto.

Fig. 2, is a front elevation of one of 30 coupled snare carrying mechanisms.

Fig. 3, is a similar view with the parts removed.

Fig. 4, is a horizontal section on line 4—4, 35 Fig. 1.

Fig. 5, is a detail vertical section on line 5—5. Fig. 2.

Like reference numerals indicate like parts in the several views.

Referring to the drawing, 1 designates 40 the usual main cylindrical shell of a drum having at each end a straining hoop 2, with each of said straining hoops comprising the usual skin hoop 2', and an external hoop 2 associated with said skin hoop to form a 45 raised circular rim beyond the head or skin 3. Said external hoop is preferably formed of metal have the offset or Z form shown in Fig. 1.

4 designates the drum snare of any usual 50 formation, which in this construction is attached at its respective ends to carrying members 5 and 5' having movement in

planes at right angles to the head or skin 3 of the drum in the simultaneous manner hereinafter described to attain a uniform 55 adjustment of the entire snare to and from contact with said drum head. In the attainment of the above mentioned simultaneous movements of the parts, as well as the initial tensioning of the snare member 60 itself, a counter-part construction and arrangement of parts at opposite sides of the drum is employed as follows:

6 designates a base plate or member secured to an outer face of the shell 1 and 65 formed with a journal orifice for the hereinafter described crank hub and with upper guide ears 7 and lower guide flange 8 for guiding the intermediate companion plate or slide now to be described. 70

9 designates the intermediate plate or slide adapted for guiding engagement in the guide ears 7 and flanges 8 aforesaid, to move in a plane parallel with the face of the shell 1 and in a plane at right angles 75 to the face of the drum head or skin 3. Near its mid-length the slide 9 is formed with a transverse slot 10 for operative engagement with the crank pin or block of the operating hub hereinafter described, and at its 80 lower end the slide 9 is provided with a flange 11 to afford a bearing for the adjusting screw of a cross head as follows.

12 designates a cross head having sliding engagement with the lower portion of the 85 slide 9 and formed with a central lug 13 having a screw threaded orifice for engagement with the screw threaded shank of an adjusting thumb screw 14 which is revolvably mounted in the aforesaid flange 11 of 90 the slide 9, so that by a manual turning of said screw, the cross head 12 is adjusted as desired along the slide 9 for the purpose hereinafter set forth.

15 designates a revoluble hub formed with 95 an offset in its periphery for bearing engagement in the above described bearing orifice of the fixed base plate 6 and having an axial bore of any usual non-circular formation adapted to engage with an end 100 of the connecting shaft hereinafter described so that the parts will turn in a simultaneous manner. In the construction shown the non-circular formation of said

axial bore is attained by radial slots 16 connecting with said bore and adapted to receive cross pins of said connecting shaft.

17 designates a crank pin mounted in the 5 outer face of the hub 15, preferably of the rectangular form shown and having operative engagement with the transverse slot 10 of the slide 9 aforesaid, so that with a turning movement of the hub a vertical 10 movement will be imparted to the slide 9. In such preferred construction of the crank pin 17 the same is provided with a circular shank 18 fitting and turning in a corresponding orifice in the hub 15, and held in 15 place by the engagement of the inner portion of the hereinafter described rod or handle in a circumferential groove in said shank 18 as shown more particularly in Fig. 5.

20 19 designates the connecting shaft above referred to, extending across the interior of the drum shell 1 and having non-circular ends adapted to engage the like non-circular bores of a pair of hubs 15 arranged at 25 opposite sides of the shell 1 to impose simultaneous revolution on said hubs in a manual turning adjustment of either hub.

20 20 designates an operating rod or handle extending radially from a hub 15 for convenient manual turning movement of the hub, and in the construction shown the inner portion of the rod presses transversely through the hub 15 and is riveted or otherwise fixedly secured in place.

25 35 Each of the counterpart snare carrying members 5, 5' aforesaid is formed with an upper semi-circular or arched portion 21 adapted to overhang an adjacent portion of a strain hoop 2, and with a depending 40 shank portion 22, the lower end of which is pivotally connected to the aforesaid cross head 12, preferably by a return bend 22' engaging the rear edge of the cross head 12 and held in place by contact with the adjacent face of the associated slide 9, as 45 shown more particularly in Fig. 5. The free and inner end of arched portion 21 of a carrying member is laterally widened and has a flanged form as shown adapted to afford a substantial holding abutment for 50 one end of the snare member 4, which is clamped in place thereon by a holding bar 23 and a plurality of clamping screws as shown in Figs. 1 and 2.

55 55 24 designates an adjusting thumb screw passing through the upper portion of the shank portion 22 of the carrying member and having bearing against the upper end of the slide 9, preferably by a reduced end 60 of said screw having bearing engagement with a vertical groove on slot 25 in the upper portion of the slide 9.

In the practical use of the present construction, the respective ends of the drum snare 4 are secured to the respective hold-

ing ends of the carrying members 5, 5' in an even and proper manner, after which the proper tensioning of the snare is effected by one or the other, or by both of the thumb screws 24.

The vertical adjustment of the respective ends of the snare 4 to attain proper relation to the drum head or skin is then effected by one or the other of the adjusting thumb screws 14.

With the above described initial adjustments effected, the snare mechanism is ready for actual use, and so that by a partial rotation by hand of the connected crank hubs 15 simultaneous movement is imparted 75 to the snare carrying members 5, 5' in paths at right angles to the face of the drum head or skin 3, to bring the snare 4 into uniform contact with the drum head or skin along the entire length of the snare, or to remove 80 the snare from such contact in a like manner. With the movement of the parts in the manner described, the initial tensioning of the snare is preserved during the different and repeated movements of the same to and 85 from the drum head or skin.

Having thus fully described my invention what I claim as new and desire to secure by Letters Patent, is:—

1. A drum having a snare extending 90 across the head of the same, a pair of snare supporting members mounted at opposite sides of the drum, and means for imparting simultaneous movement to said members in a path at substantially right angles to the 100 face of the drum head.

2. A drum having a snare extending across the head of the same, a pair of snare supporting and tensioning members mounted at opposite sides of the drum, means for 105 effecting a tensioning adjustment of said members, and means for imparting simultaneous movement to said members in a path at substantially right angles to the face of the drum head.

3. A drum having a snare extending across the head of the same, a pair of snare supporting members mounted at opposite sides of the drum, revoluble operating hubs 115 individual to the snare supporting members, and a connecting rod extending between said hubs and adapted to impart simultaneous rotation thereto.

4. A drum having a snare extending across the head of the same, a pair of snare supporting and tensioning members mounted at opposite sides of the drum, means for 120 effecting a tensioning adjustment of said members, revoluble hubs individual to said members, and a connecting rod extending between said hubs and adapted to impose simultaneous rotation thereon.

5. A drum having a snare extending across the head of the same, a pair of snare supporting members mounted at opposite 125

- sides of the drum, revoluble crank hubs individual to said members and adapted to impart movement to the same in a path at substantially right angles to face of the drum head, and a connecting rod extending between said hubs and adapted to impart simultaneous rotation thereto.
6. A drum having a snare extending across the head of the same, a pair of snare supporting and tensioning members mounted at opposite sides of the drum, means for effecting a tensioning adjustment of said members, revoluble crank hubs individual to said members and adapted to impart movement to the same in a path at substantially right angles to the face of the drum head, and a connecting rod extending between said hubs and adapted to impart simultaneous rotation thereto.
10. A snare mechanism comprising, a base plate adapted for attachment to the body of a drum and formed with a journal orifice, a revoluble hub journalled in said orifice and having a crank pin, an intermediate plate 65

slidably connected to said base plate and operatively connected to the crank pin of said hub, a snare carrying member pivotally connected to said intermediate plate, and means for imparting independent pivotal adjustment to said carrying member to tension the snare attached thereto.
7. A snare mechanism comprising, a base plate adapted for attachment to the body of a drum and formed with a journal orifice, a revoluble hub journalled in said orifice and having a crank pin, an intermediate plate 70

member to tension the snare attached thereto. 15

14. A snare mechanism comprising, a base plate adapted for attachment to the body of 5 a drum and formed with a journal orifice, a revoluble hub journalled in said orifice and having a crank pin, an intermediate plate slidingly connected to said base plate and operatively connected to the crank pin 10 of said hub, a snare carrying member having a lower shank portion pivotally connected to said intermediate plate and an upper portion of an arched shape the free

end of which is provided with attaching means for the end of a snare, a screw arranged intermediate of said plate and member and adapted to effect an independent pivotal adjustment of the carrying member to tension the snare attached thereto, and another screw arranged intermediate of said plate and member for effecting a sliding movement of said carrying member upon the aforesaid intermediate plate. 20

Signed at Chicago, Illinois, this 31st day 25 of May, 1921.

ROBERT C. DANLY.
